UNITED STATES PATENT OFFICE.

OKEY HILL DE VAUGHN, OF PARKERSBURG, WEST VIRGINIA.

SADDLE-SPRING FOR DRILLS.

1,172,679.

Specification of Letters Patent.

Patented Feb. 22, 1916.

Application filed July 26, 1915. Serial No. 41,978.

To all whom it may concern:

Be it known that I, OKEY HILL DE VAUGHN, a citizen of the United States, residing at Parkersburg, in the county of Wood and State of West Virginia, have invented certain new and useful Improvements in Saddle-Springs for Drills; and I do declare the following to be a full, clear, and exact description of the invention, such 10 as will enable others skilled in the art to which it appertains to make and use the same.

This invention relates to improvements in drilling machines and more particularly 15 to saddle springs therefor.

The object of the invention is to provide a simply constructed and efficient device of this character for use in connection with wire lines or soft cables to prevent jars on 20 the rig or derrick and which is designed to be mounted on the walking beam of the apparatus.

With this and other objects in view, the invention consists of certain novel features 25 of construction and the combination and arrangement of parts as will be more fully described and claimed.

In the accompanying drawings; Figure 1 represents a side elevation of one end of a 30 walking beam showing this improved saddle spring applied; Fig. 2 is a horizontal section taken on the line 2—2 of Fig. 1; Fig. 3 is an end elevation thereof.

In the embodiment illustrated this improved device is shown applied to the upper 35 face of a walking beam W B of the usual construction and said device comprises a substantially rectangular frame composed of a base plate 1 here shown rectangular in 40 form although obviously it may be of any other desired configuration and which is provided at its corners with standards 2 rising therefrom and which are here shown composed of angle irons L-shaped in cross 45 section. The flanges 3 of said standards at the sides of the base plate 1 project at their upper ends above the other flanges thereof and are apertured to provide bearings for rods or bolts 4 and 5 which extend 50 transversely across the frame through the apertures in the upper ends of the flanges 3 and which are designed to support the opposite ends of a top plate 6. This top plate

6 is of a width equal to the distance between the apertured side flanges 3 of the opposed standards as is shown clearly in Fig. 2 and the ends of said plate are rolled downwardly and inwardly to form bearings 7 through which the bolts 4 and 5 pass and connect said top plate to the standards 2. 55 60

The base plate 1 is shown provided with a plurality of upwardly extending bosses 8 any desired number of which may be employed, eight being here shown arranged in two parallel rows of four each and which are designed to receive one end of coiled cushioning springs 9 hereinafter more fully described. This base plate 1 is secured to the walking beam W B by bolts 10 which extend through apertures suitably disposed 70 in said plate and vertically through the walking beam, as clearly shown in Fig. 1 and by means of which said plate is reliably secured to said beam.

The top plate 6 is provided on its inner 75 face with a plurality of depending bosses 11, any desired number of which may be employed, four being preferably employed arranged at the opposite corners respectively of said plate. These bosses 11 and 80 the bosses 8 of the base plate are both shown herein as cylindrical in form, the bosses 11 being smaller than the bosses 8 to receive the inner ends of coiled springs 12 which are smaller than the springs 9 supported on 85 the bosses 8 of the base plate.

An intermediate plate or head 13 is mounted to move vertically between the base and top plates and is of a length to adapt it to fit between the flanges of the 90 standards so that these flanges form guides for said head to retain it against longitudinal and lateral displacement. This intermediate plate 13 is provided on its lower 95 face with a plurality of depending bosses 14 which correspond in shape and number to the bosses 8 of the base plate and are positioned to register therewith and to receive the upper ends of the coiled springs 9 as is shown clearly in Fig. 1. This intermediate plate 13 is also provided at its opposite side edges with longitudinally extending ribs 15 which taper toward their opposite ends and are provided at their central wider portions with notches 16 which register with each other and are designed to re- 100 105

ceive a stirrup C which is connected with the crank shaft (not shown). The head 13 is also provided on its upper face with upwardly extending bosses 17 which register 5 with the bosses 11 on the top plate and correspond in shape and number therewith and are designed to receive the lower ends of the cushioning springs 12. The springs 12 are shown more closely coiled than the 10 springs 9 and hence the cushioning effect thereof varies correspondingly.

From the above description it will be obvious that the springs 9 and 12 cushion the movement of the intermediate plate 13 in 15 both directions, a downward pull exerted on the end opposite that carrying the saddle serving to raise the saddle carried end and compress the springs 9 and on the release of said pull these springs expand and thus 20 cushion or break the direct vibration from the tools to the crank and thus all jars on the crank shaft are prevented, said springs operating as shock absorbers.

From the above description and an inspection of Fig. 1 it will be understood that the springs 9 are normally expanded and force the head 13 and beam W. B. away from each other, thereby compressing springs 12 between said head 13 and the top 25 plate 6; and when a pull down is exerted on the stirrup C the springs 9 are compressed while springs 12 expand and thereby cushion the movement of the walking beam in both directions and when the pull on the 30 stirrup is released, the springs 9 expand and springs 12 contract thus cushioning the upward movement of the beam.

It is of course understood that the cable or wire line is connected with the other end 35 of the walking beam W. B. (not shown).

The springs 9 and 12 in the structure above described may be removed and others of different tension substituted when desired according to the weight they are to 40 support as it will be understood that with drilling machines the depth of the hole being drilled controls the weight carried by the springs.

I claim as my invention:

50 1. In a device of the class described the combination of vertically spaced plates held in fixed relation to each other, an intermediate plate movable between said fixed plates and provided with stirrup supporting means, and cushioning springs arranged between said intermediate plate and the base plate and also between said intermediate plate and the top plate.

2. In a device of the class described the 55 combination of vertically spaced plates held in fixed relation to each other, an intermediate plate movable between said fixed plates and provided with stirrup supporting means, cushioning springs arranged be-

tween said intermediate plate and the base 65 plate and also between said intermediate plate and the top plate, and means carried by said base plate for guiding said intermediate plate and holding it against longitudinal and lateral displacement.

3. In a device of the class described the combination of a base plate, standards rising therefrom, a top plate mounted on said standards, a plate movably mounted between said top and base plates, cushioning 75 springs arranged between said movable plate and said base plate and between said movable plate and top plate, and means carried by said plates for holding said springs in operative position.

4. In a device of the class described the combination of a rectangular base plate, standards rising from the corners thereof, said standards being in the form of angle irons L-shaped in cross section, the flanges 85 at the sides of said standards being longer at their upper ends than the other flanges and apertured to form bearings, a top plate of a width equal to the distance between the apertured ends of the opposed standards 90 and having their ends rolled to form bearings, bolts extending through the bearings in said standards and through those of the ends of said top plate, laterally extending bosses on the inner faces of said top and 95 base plates, an intermediate plate arranged between said top and base plates and having bosses on both faces registering with those of the opposed plates, coiled springs arranged between said base and intermediate 100 plates with their ends engaging the bosses thereof, similar springs between said intermediate and top plates with their ends engaged with the bosses thereof, and means carried by said intermediate plate for supporting a stirrup.

5. In a device of the class described the combination of a rectangular base plate, standards rising from the corners thereof, said standards being in the form of angle irons L-shaped in cross section, the flanges 110 at the sides of said standards being longer at their upper ends than the other flanges and apertured to form bearings, a top plate of a width equal to the distance between the 115 apertured ends of the opposed standards and having their ends rolled to form bearings, bolts extending through the bearings in said standards and through those of the ends of said top plate, laterally extending 120 bosses on the inner faces of said top and base plates, an intermediate plate arranged between said top and base plates and having bosses on both faces registering with those on the opposed plates, coiled springs 125 arranged between said base and intermediate plates with their ends engaging the bosses thereof, similar springs between said

intermediate and top plates with their ends engaged with the bosses thereof, longitudinally extending transversely spaced ribs on the upper face of said intermediate plate 5 provided with registering notches to receive a stirrup.

In testimony whereof I have hereunto set

my hand in presence of two subscribing witnesses.

OKEY HILL DE VAUGHN.
